United States Patent [19]

Marchesi

[11] Patent Number: Des. 434,505

[45] Date of Patent: ** Nov. 28, 2000

[54] **MICROELECTRIC UNIT FOR PRODUCING STIMULI FOR TREATMENT OF THE HUMAN BODY**

[76] Inventor: **Fabio Paolo Marchesi**, Via Tadino, 13, 20124 Milano, Italy

[**] Term: **14 Years**

[21] Appl. No.: **29/115,372**

[22] Filed: **Dec. 14, 1999**

[30] **Foreign Application Priority Data**

Jun. 17, 1999 [IT] Italy MI9900356

[51] **LOC (7) Cl. 24-04**

[52] **U.S. Cl. D24/200; D24/188**

[58] **Field of Search** D24/200; 607/2, 607/46, 50, 51, 62, 68-72

CLAIM

I claim the ornamental design for a microelectric unit for producing stimuli for treatment of the human body, as shown.

DESCRIPTION

FIG. 1 is a perspective view of a microelectric unit for producing stimuli for treatment of the human body, showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a left side elevational view thereof; and,

FIG. 7 is a right side elevational view thereof.
